United States Patent

Des. 238,098
Patented Dec. 16, 1975

238,098

PORTABLE RADIO

David H. Fink, 52 Fox Lane, Dix Hills, N.Y. 11746

Filed Mar. 4, 1974, Ser. No. 447,658

Term of patent 14 years

Int. Cl. D14—03

U.S. Cl. D56—4 B

FIG. 1 is a front perspective view of a portable radio, showing my new design;

FIG. 2 is a rear elevational view; and
FIG. 3 is a bottom plan view.

I claim:

The ornamental design for a portable radio, as shown and described.
